UNITED STATES PATENT OFFICE

CLARENCE M. TUCK, OF SEATTLE, WASHINGTON, ASSIGNOR TO MORRIS & BOGHER, INC., OF SEATTLE, WASHINGTON, A CORPORATION

TRANSIT CONCRETE MIXER

Application filed January 26, 1927, Serial No. 163,660. Renewed January 23, 1931.

My invention relates to the art of transit concrete mixers. More particularly my invention relates to a concrete mixer mounted on an automobile truck, in which the mixer drum is fixedly mounted upon said truck.

In the concrete construction work, a large part of the expense arises by reason of the transporting of the materials, and by reason of the handling of the materials incident to loading the same into the truck and depositing the same upon the ground, and then lifting the same into mixers.

A primary object of my invention is to provide a transit concrete mixer which will serve to transport the material from the point where the said materials are constituted into batches, i. e., where the cement, sand, and the crushed rock or gravel are supplied to the truck, and then be capable of receiving water at the point of construction and thoroughly mixing the water, gravel, sand and cement by means of the power plant of the automobile, and then cause the elimination of said mixed concrete from the drum without tilting the drum itself.

A serious objection obtains to transmit concrete mixers as heretofore provided, which have the drum pivotally mounted so that it can be hoisted, as respects one end, as the method of dumping material from the ground. With the addition of the water, the weight becomes very great and, accordingly, a very powerful hoisting unit is necessary, which greatly adds to the expense of the device. Furthermore, depending upon gravity to cause the material to leave the drum is not, in practice, satisfactory, as oftentimes it does not eliminate all the material, and care and inconvenience are therefore involved in carefully cleaning the drum to prevent hardening of the concrete therein when the drum is not in use.

A primary object of my invention is to provide a positive elimination of the material. Furthermore, serious objection obtains to the pivotal drum type in providing proper power transmission means from the power plant of the automobile to the drum, to impart a rotary motion thereto for the purpose of mixing the contents.

A further primary object of my invention is to provide a transit concrete mixer having the drum fixedly mounted thereon, which is characterized by an improved mixing means which imparts a circulation in a longitudinal direction of the drum, i. e., back and forth throughout the length of the drum, which most thoroughly and efficiently mixes the contents—gravel, cement, sand and water.

A condition which obtains in mixing the elements, which go to make up concrete in a drum, is that considerably more power is required initially than after the water is distributed throughout the contents.

Another object of my invention is to provide a concrete mixer that embodies two sets of mixing blades, one set of which is disposed in a region adjacent the axis of the mixing drum and being arranged at a given angle to the radius of revolution of the shaft on which it is mounted, and the other of which blades comprise an arm portion that is securely attached to said shaft and a blade portion pivotally attached to the outer end portion of said arm portion and having resilient means attached thereto for relieving any excess pressures that may be caused upon said blade portions.

In general, a primary object of my invention is to overcome the various difficulties above set forth, and to provide a transit concrete mixer which is characterized by its efficiency and economy of construction.

The above general objects of my invention, together with others inherent in the same, are obtained by the device illustrated in the following drawings, the same being preferred exemplary forms of embodiment of my invention, throughout which drawings like reference numerals indicate like parts.

Figure 1 is a view in side elevation of a transit concrete mixer embodying my invention, with the internal portion thereof shown in dotted line.

Figure 2 is a fragmentary view in side elevation of the drum and said internal mixing parts.

Figure 3 is a view in end elevation of the drum part of my invention.

Figure 4 is an enlarged view of a detail of the same.

Upon the chassis 5 of an automobile 6, a concrete mixing drum 7 is fixedly mounted. Axially disposed in this drum is shaft 8. Upon this shaft a sprocket wheel 9 is keyed. On driving the shaft 10 of the automobile, a sprocket wheel 11 is mounted in operative relation with the clutch 12, which is operated by the lever 13. Over the sprocket wheels 9 and 11 a sprocket chain 14 is provided, whereby the power of the automobile power plant may be transmitted to the shaft 8, in an obvious manner, for actuating the said shaft.

Upon the shaft 8 a plurality of arms 15 are mounted, having blades 16 which contact the inner periphery of the mixing drum 7. The pitch of the blades 16 is such that it moves the material in the drum from the front to rear ends of the drum, i. e., in the direction of the arrows 17. Also, upon the shaft 8 are mounted a plurality of propeller blades 18, having a pitch which moves the material from the rear end of the drum to the forward end of the drum, i. e., in the direction of the arrows 19. It will be noted that these blades 18 move concentrically with the blades 16, i. e., they move in a region adjacent to the center of the drum, and do not extend to the drum itself. A water tank 20 is mounted upon the drum 7, and from this tank a pipe 21 extends rearwardly. This pipe has a plurality of perforations 22 disposed along its length, so that water may be delivered throughout the length of the drum.

The blades 16 are preferably pivotally mounted at 23 on the arms 15; also on arms 15 a relatively stiff spring 24 is mounted, and is caused to bear upon the outer edge of the blades 16.

The mode of operation of a transit concrete mixer embodying my invention, is as follows:

At the bunkers, or other suitable place where the materials are obtained, a batch of gravel, sand and cement is supplied to the drum, filling the same approximately to the level indicated by the line 25. The truck is then started towards the place of construction work. At the same time, the clutch 12 is thrown into operative engagement with the axle, and the blades 16 and 18 are caused to rotate, thereby mixing the material en route. Or, the material may not be mixed until the truck arrives at the place of location, if it is so desired. As the water is admitted to the material, it is mixed thoroughly with the solid parts, all of which are then thoroughly intermixed by means of the two sets of rotating blades, i. e., by the blades which move in contact

with the periphery of the drum, and the shorter blades which revolve in the region adjacent to the axis of the drum.

Manifestly, the blades 16, disposed in staggered relation along the shaft 8, gradually cause the material to move from the forward end to the rear end of the drum. In so doing, they pick up the material lying adjacent to the periphery of the drum, and cause it to be lifted upwardly in the drum, causing the material to assume the general level indicated by line 25', Figure 3, while, at the same time, causing it to move rearwardly of the drum. At the same time, the blades 18, mounted on the same axis and revolving in the same direction, but having a pitch in the opposite direction to the more outwardly disposed blades 16, cause the material in the central portion of the drum to move to the forward end of the drum, thereby creating a circulation back and forth through the drum, and thoroughly intermixing all of the ingredients. When the location of construction is reached, it is only necessary to open the door 26, and the material is then positively forced out of the drum, and the revolving blades 16 overlapping each other in their orbits, must thoroughly scrape and clean the inside of the drum, positively ejecting all of the contents from the drum so that no delay is incident to cleaning out the drum.

It will be noted that when the shaft 8 first starts to revolve, the material will be dry and a considerable extra effort will be necessary to mix the material. However, as the blade 16 is pivotally mounted at 23, somewhat above its center, the spring 24 permits the blade to tilt backward, as shown in Figure 4; thereby a smaller contacting face is presented by the blade against the material, or, in other words, a smaller quantity of material is moved by the blades, so that the power applied to the shaft 8 is more efficiently utilized in agitating the material as the material becomes saturated with water, and as it becomes more mobile, the resistance encountered by the blade 16 will be less, and the spring 24 automatically gradually causes the blade 16 to assume the radial position shown in full line, Figure 4, so that in this position it is capable of moving the maximum amount of material.

Thus is afforded a transit concrete mixer which is characterized by simplicity of construction and most efficient operation.

Obviously, changes may be made in the forms, shape of mixing drum, dimensions and arrangement of the parts of my invention, without departing from the principle thereof, the above setting forth only a preferred form of embodiment.

I claim:

1. A concrete mixer embodying a fixed mixer drum, a horizontal driven shaft op-

- eratively mounted within said drum, a center set of mixing and propelling blades secured to said driven shaft, said central blades disposed to rotate in a region adjacent
5 the axis of the drum, radially disposed arms secured to the driven shaft, outer mixing and propelling blades of opposite pitch to the central blades pivotally secured to said arms, the pivot axis being displaced sufficiently from the axis of the blade as to cause the blade to partially revolve when it meets with resistance on its face, resilient means causing the outer blades, to normally present their maximum working face.
- 10 2. A concrete mixer embodying a fixed mixing chamber, a horizontal driven shaft operatively mounted within said chamber, short mixing and propelling blades secured to the driven shaft and pitched to propel material forward, radially disposed arms secured to the driven shaft, outer mixing and propelling blades pivotally secured to said arms and pitched to move material near the shell, rearward, a pivot for said outer blades
20 25 the axis of which being only slightly displaced from the longitudinal axis of the blade and resilient means adapted to normally maintain the blade with its maximum working surface presented to the material
30 to be mixed.
3. In a horizontal concrete mixer, a mixing and propelling blade mounted on a working pivot and resiliently held in its operating position, supported on a driving means
35 with its pivot axis slightly displaced from its longitudinal axis, this displacement being of sufficient amount that the resistance encountered by the larger portion will overcome the resistance offered by the smaller portion plus the resistance of the resilient means and cause the blade to revolve thus lessening the total effort required to pass the blade through the mix.

40 Signed at Seattle, in the county of King
45 and State of Washington, this 21st day of January, 1927.

CLARENCE M. TUCK.
